UNITED STATES PATENT OFFICE.

HARRY J. POTTER, OF CAMBRIDGE, MASSACHUSETTS, ASSIGNOR TO BURNITOL MANUFACTURING COMPANY, OF CAMBRIDGE, MASSACHUSETTS, A CORPORATION OF MAINE.

SPUTUM-CUP.

No. 920,180.

Specification of Letters Patent.

Patented May 4, 1909.

Application filed June 4, 1906. Serial No. 319,978.

To all whom it may concern:

Be it known that I, HARRY J. POTTER, a citizen of the United States, and a resident of Cambridge, in the county of Middlesex, 5 State of Massachusetts, have invented an Improvement in Sputum-Cups, of which the following description, in connection with the accompanying drawings, is a specification, like characters on the drawings representing 10 like parts.

This invention relates to receptacles adapted, among other purposes, for use as a sputum cup, for the sick room, hospitals and wherever such cups are used. A cup for such 15 use, should be of light weight, and provided usually with a cover.

My invention provides a cup, which, while possessing all the good qualities of cups heretofore used, possesses the additional important advantage, that, being inexpensive to 20 manufacture, it may, after reasonable, usually one use, be destroyed, thus avoiding the necessity of cleansing it frequently, saving the time and labor necessitated by such 25 cleansing, as well as avoiding the danger arising from lack of proper cleansing.

Although the cup may be made from different kinds of material, it is preferably made from heavy paper, previously rendered 30 water proof and may be made from a blank previously cut from a single sheet of material and so folded that it is perfectly tight.

While my invention may be embodied in many different forms the one selected for 35 illustration herein is preferred, it being provided with a handle, a self-closing cover, and an infolded flange to prevent accidental falling out of the roll of cotton or similar material commonly used in such cups.

40 Referring to the drawings:—Figure 1 is a perspective view of a cup comprising my invention showing the cover raised. Fig. 2 is a sectional view from the right of said cup on the line $x-x$, Fig. 1; Fig. 3 is a sectional view of the cup from the front on the line $y-y$, Fig. 1; Fig. 4 is a view of the cup from 45 the right hand side, showing the cover partially broken off, the body of the cup completed with locking members in locking position, but before the flange has been turned; Fig. 5 is a plan view of the cover, and Fig. 6

is a view of the blank from which the cups are made, showing the method of scoring and folding the blank to form the cup.

Referring to Fig. 6 of the embodiment of 55 my invention shown herein, the blank A, shaped as shown, is first scored along lines 1—1, thus outlining the bottom of the cup. By scoring along the lines 2—2 and 3—3 the sides 4—4 and front 5 and back 6 of the cup 60 are formed, leaving between the sides 4—4 and front 5 and back 6 the corner pieces 7—7 and providing the respective sides, front and back with extensions 8—8. For convenience of description, the sides 4—4, the front 65 5, and the back 6, may be termed side portions. These extensions 8—8 are provided with the slots 9—9, and the locking members 10—10, as shown, adapted to enter the slots and lock the various parts of the receptacle 70 securely together.

The corner parts 7—7 are scored along lines 11—11 permitting them to be folded adjacent the sides of the receptacle and the extensions 8—8 are scored along lines 75 12—12, 13—13 and 14—14 forming the flanges.

The extension 8 of the back 6 of the cup is provided with a neck like member 15 scored at 16 to permit it to be folded inwardly over the flange at the back of the cup. This member 15 is cut along the line 17 and scored in the line 18, thus forming a tongue like member 19 which stands upright and to which the cover is hinged when 80 the part 20 is bent downwardly adjacent the back of the cup. Part 20 is then cut along lines 21 and 22—22 and scored along lines 23, 24 and 25 preparatory to forming the handle 26. 90

To form the cup the blank scored as above described is first folded upward along lines 1—1 thus forming the bottom. The sides 4—4 and front 5 and back 6 being brought to an upright position, the corner sections 95 7—7 are folded inwardly along lines 11—11, forming triangular wings which are then pressed adjacent the sides of the cup, bringing the slots 9—9 on each side opposite to each other and in position to receive the 100 locking members 10—10 for the respective sides. The locking member 10, provided

with shoulders 29, is then inserted through the slots 9—9, locking the sides securely. The triangular corner pieces 28—28 of the front and back extension 8—8 are then in-
5 folded along lines 12—13—14 and the parts 8—8 then turned inwardly, forming flanges which serve to retain in the cup the roll of cotton or similar substances which is cus-
tomarily used in such receptacles and com-
10 pleting the formation of the cup proper. The part 20 is then turned downwardly ad-
jacent the back of the cup, the parts 26 form-
ing the handle folded outwardly on lines 23
and 25 and brought together on line 24, and
15 part 27 laid adjacent the part 20 at the back
of the cup. The parts 20 and 27 may now
be secured to the back of the cup by any
suitable adhesive and the cup is complete.
The handle 26 being flexible may be folded
20 against the back of the cup for convenience
in packing, if desired. The tongue 19 re-
maining in an upright position serves as a
hinge member for the cover 30 in connection
with the slot 31 therein.
25 The cover is of regular outline and pro-
vided at its sides with shouldered portions
herein represented as slots 32—32 to engage
an elastic band 33 or other suitable spring
member which encircles the cup to cause the
30 cover to close automatically when released
from pressure at the finger piece 34 provided
at the back edge of the cover.

Claim.

1. As a new article of manufacture a recep-
35 tacle of the class described comprising a body
formed from a single sheet of material shaped
and scored to present a bottom, side walls
extending therefrom and provided with in-
folding extension pieces integral therewith,
40 one of said extension pieces being provided
with a portion extending therefrom in line
therewith, said latter extension portion being
adapted to be folded back over said extension
piece and down over the corresponding side
45 wall and cut to form a tongue member near
the top of said side wall, and also cut to form
a handle member adapted to be bent out at an
angle to said side wall beneath the tongue,
and a cover hinged upon said tongue member
50 and having a portion thereof extending above
said handle member.

2. As a new article of manufacture a recep-
tacle of the class described, comprising a
body formed from a single sheet of material
55 shaped and scored to present a bottom, side
walls extending therefrom, one of said side
walls being provided with a portion extend-
ing therefrom in line therewith, said exten-
sion being adapted to be folded back and
60 downward over said latter side wall, and cut
to form a tongue member near the top of
said side wall, and also cut to form a handle
member adapted to be bent out at an angle
to said side wall beneath the tongue, and a

cover hinged upon said tongue member and 65
having a portion thereof extending above
said handle member.

3. As a new article of manufacture, a recep-
tacle comprising a body formed from a single
sheet of flexible material scored to present a 70
bottom portion, side portions extending
therefrom, corner portions between said side
portions and an extension piece extending
from one of the side portions and shaped so
as to be folded outwardly and downwardly 75
over that side portion of the receptacle from
which it extends, a handle piece formed in
said extension piece and adapted to be bent
therefrom and extend outwardly from the
side of the receptacle. 80

4. As a new article of manufacture, a recep-
tacle comprising a body formed from a single
sheet of flexible material scored to present a
bottom portion, side portions extending 85
therefrom, corner portions between said side
portions, and extension pieces extending
from the side portions and adapted to be
folded and interlocked to form an inwardly
extending flange about the mouth of the re-
ceptacle, one of said extension pieces being 90
continued to form a portion which is adapted
to be bent back at the edge of the flange and
extend downwardly over that portion of the
receptacle of which it is a continuation, and a
tongue member cut from said extension and 95
adapted to project near the upper edge of the
receptacle and a cover for the receptacle,
said tongue forming a hinge member for said
cover.

5. As a new article of manufacture, a re-
ceptacle comprising a body formed from a 100
single sheet of flexible material scored to pre-
sent a bottom portion, side portions extend-
ing therefrom, corner portions between said
side portions, and an extension piece extend-
105 ing from one of the side portions and shaped so
as to be folded outwardly and downwardly
over that side portion of the receptacle from
which it extends, a handle piece in said ex-
tension piece and adapted to be bent there-
110 from and extend outwardly from the side of
the receptacle, and a cover hinged upon the
receptacle and adapted to be operated by the
thumb upon that hand of the user grasping
said handle piece. 115

6. As a new article of manufacture, a re-
ceptacle of the class described comprising a
body formed from a single sheet of material
shaped and scored to present a bottom, side
120 walls extending therefrom, infolding corner
portions between the side portions and in-
folding extension pieces 8, one pair of in-
folding extension pieces 8 being formed as
continuations of opposite side walls and in-
folding corner walls, each of said pair of ex-
125 tensions having at opposite ends a slot and an
extended tongue, the other pair of extensions
8 each extending from and in line with the

other pair of the side walls of the receptacle and each provided with a slot, each tongue of said extensions being adapted when the receptacle is shaped to enter two of said slots and said extensions 8 being adapted to be unfolded to form a retaining flange.

5 In testimony whereof, I have signed my

name to this specification, in the presence of two subscribing witnesses.
